UNITED STATES PATENT OFFICE.

ELMER E. WICKERSHAM, OF STOCKTON, CALIFORNIA, ASSIGNOR TO THE HOLT MANUFACTURING COMPANY, OF STOCKTON, CALIFORNIA, A CORPORATION OF CALIFORNIA.

TRACTION-ENGINE.

1,356,679.

Specification of Letters Patent. Patented Oct. 26, 1920.

Application filed January 18, 1918. Serial No. 212,383.

To all whom it may concern:

Be it known that I, ELMER E. WICKERSHAM, a citizen of the United States, residing at Stockton, in the county of San Joaquin and State of California, have invented new and useful Improvements in Traction-Engines, of which the following is a specification.

This invention relates to traction engines 10 of the type in which the entire weight of the vehicle is supported upon a pair of endless, self-laying track mechanisms and in which steering is effected by varying the relative speed of said track mechanisms. It will be 15 manifest that the invention is capable of wider application.

The chief object of the invention is the improvement in steering means which has heretofore generally been accomplished 20 through the medium of friction clutches. In the present invention the steering is done through the medium of reduction gears of the planetary type located in the hub or hubs of the driving member or members and controlled by a band brake.

A further object involves the novel arrangement of parts whereby the usual tractor frame is eliminated, the truck frames of the self-laying track mechanisms 30 being directly secured to the motor crank case and hollow extensions thereof, and whereby the usual steering friction clutches are replaced by reduction gears carried within each drive sprocket. The tractor as a 35 whole may thus be constructed with a minimum width equal to the sum of the widths of the two tracks and the motor crank case and yet be provided with positive steering and driving gears of substantial dimensions 40 for each track. The actuation of the track driving sprockets, by means of interiorly located planetary gears, accomplishes also a further result.

As heretofore constructed tractors of the 45 type involved had the drive sprockets journaled on a stationary shaft, the internal gear in the sprocket being driven by a pinion on a separate drive shaft, whereas in the present invention the internally driven 50 sprocket is journaled directly on the drive shaft, thus equalizing the distribution of power and the stresses on the various parts.

A preferred form of the invention is exemplified in the following description and

illustrated in the accompanying drawings, 55 in which—

Figure 1 is a front elevation of a tractor embodying the invention, the links of the forward vertical run of the tracks being removed.

Fig. 2 is a similar view of the rear end of the tractor, part of the housing being broken away to show the bevel gear and pinion.

Fig. 3 is a fragmentary detail elevation of the pivotal connection between the crank 65 case and equalizer spring.

Fig. 4 is a similar view of the connection between the truck frames and the ends of the equalizer spring.

Fig. 5 is a side elevation of the tractor, 70 the upper run of the track being shown in dotted lines.

Fig. 6 is a plan view of one of the roller trucks.

Fig. 7 is a cross sectional view of the 75 roller truck frame, taken on the line 7—7 of Fig. 5.

Fig. 8 is a similar view on line 8—8 of Fig. 5.

Fig. 9 is a plan view of the tractor with 80 the tracks removed.

Fig. 10 is an elevational, sectional view of one of the drive sprockets taken on line 10—10 of Fig. 11.

Fig. 11 is a cross-sectional view of the 85 drive sprocket, taken on line 11—11 of Fig. 10.

As shown in the drawings, the particular embodiment of the invention described herein comprises a motor 12, preferably of the 90 eight cylinder internal combustion type. The crank case 13 of motor 12 is provided with a hollow extension 14 at one end and a cylindrical boss 15 at the other, these members forming means to connect the motor 95 to the self-laying track mechanisms in a manner to be described presently. It will thus be noted (see Fig. 9) that the tractor has not the usual main frame upon which the various mechanisms are supported and 100 to which the self-laying track mechanisms are secured. On the contrary, it consists merely of a pair of self-laying track mechanisms and a motor arranged between them in a manner to hold them in position and 105 deliver power to them. The motor 12 is provided with a suitable radiator 16 carried on arms 17 secured to the motor.

The hollow extension 14 of the crank case 13 extends rearwardly and opens into a transversely disposed casing 19. The housing thus formed incloses change speed gears shown diagrammatically at 20, a propeller shaft 21 and a transverse driving shaft 22 carried in casing 19. Secured on either side of casing 14 are stub axles 23, fitted into bosses 24 on the casing 14. These axles 23 serve to support the rear end of the motor and connected mechanism on the roller truck frames 25. Suitable journal boxes 26 are carried on the rear ends of frames 25 for this purpose.

15 The front end of the motor is supported upon an equalizer bar, preferably consisting of a semi-elliptical spring, such as that shown at 27. The spring 27 is pivotally secured at its center to the motor by means 20 of shackles 28 having a yoke 29 engaging the boss 15 on the front end of the crank case 13. The outer ends of the spring 27 are fastened to the forward extremities of the frames 25 by means of clips 30. As 25 shown in Fig. 4, these clips are preferably formed with inwardly curved dependent members 31 properly shaped to fit the forks of the truck frames.

30 The roller truck frames are struck out or punched from the blank stock in a manner to form one-piece frame members 25, having a U-shaped cross section. As shown in Fig. 7, the lower edges of the inverted channel member thus formed are turned outwardly 35 forming flanges 32. The forward ends of frames 25 are forked, as shown in Fig. 6, the material from the central portion of the cross web of the channel member being formed into flanges 33, as shown in Fig. 40 8. A cross flange or strengthening rib 34 is formed on the upper side of the cross web of the channel member at the base of the forks, being in fact an upturned continuation of and connection between the flanges 45 33 (see Fig. 5).

Carried on the forward end of the frames 25 and embracing the forks therein are yokes 35. These yokes are provided at their outer ends with journal boxes 36, in which are 50 mounted the axles of track carrying idler wheels 37. The yokes 35 are adjustably secured to the frames 25 by brackets 38 engaging the flanges 33, as shown in Fig. 1, and by adjusting screws 39 and brackets 40. 55 By operating the screws 39 it is thus possible to move the yokes backward or forward to regulate the tension of the endless tracks.

60 The truck frames are supported upon suitable endless, self-laying tracks shown at 41, by means of a series of flanged rollers 42 journaled between the depending sides of the channel shaped frames 25 on axles carried in journal boxes 43 secured to flanges 32. The truck frames are also provided with 65 means to support the upper run of tracks 41,

the means herein illustrated comprising rollers 44 carried on upstanding brackets 45.

Power to drive the tracks is delivered from the motor through change speed and reverse gears, shown diagrammatically at 20, 70 to a propeller shaft 21. The usual master clutch with a foot pedal 46 is interposed between the motor and the change speed gears and housed in the crank case 13. A suitable gear-shifting lever 47 is journaled in a cover 75 plate 48 on the housing 14. The shaft 21 transmits power through bevel gearing 49 to the transverse driving shaft 22, which in turn drives the track-carrying and driving sprocket wheels 50, which are carried on 80 the outer ends of said shaft.

Carried within sprocket wheels 50 and connected to the ends of drive shaft 22 are planetary gear mechanisms by which the relative speed of the drive sprockets may be 85 varied. Since both of these mechanisms are alike the description will be simplified by explaining only one of them. Referring to Figs. 10 and 11 it will be seen that the sprocket wheel comprises an outer toothed 90 rim 51, preferably of cast steel and formed with laterally extending flanges 52 by which the rim may be secured in place upon a pressed steel drum or hub 53. The flanges 52 also serve as a support for the rails of 95 the track while passing around the wheel. By thus making the wearing portion of the sprocket wheel removable it is possible to make it of high grade and expensive material without increasing the cost of manufacture. This construction also facilitates replacement of worn sprockets and decreases the cost of such replacements.

100 The outer end of the drum or hub 53 is preferably formed integrally with the cylindrical sides of said drum and provided with a central aperture in which is secured a journal box 54 fitted with roller bearings 55 to receive the ends of the drive shaft 22. The inner end of the drum is closed by 110 means of a disk 56, having a flange 57 at its outer edge by which it may be secured to the walls of the drum. A collar 58 formed about a circular aperture at the center of disk 56 serves as an inner bearing for the 115 sprocket wheel as a whole. The interior of the collar 58 is provided with an oil retaining felt washer 59. The central drum or hub of the sprocket wheel thus forms an oil and dust-proof case which may be partly 120 filled with oil to lubricate the incased gears and bearings.

125 The hub 53 is driven by means of an annular internal gear 60, secured interiorly thereof, and meshing with a set of planetary gears 61, journaled on roller bearings 62 and pins 63 carried by arms 64 formed on a sleeve 65. This sleeve is journaled within and extends outwardly from the collar 58 and surrounds the shaft 22 upon which it is 130

rotatably carried by means of roller bearings 66. The outer ends of pins 63 are secured in position by means of a circular plate 67 provided at spaced intervals with 5 holes through which said pins are inserted, as shown in Fig. 10. Gears 61 are driven by a pinion 68 keyed on shaft 22 between the bearings 66 and 55.

Secured exteriorly of the hub 53, on the 10 outer extension of the sleeve 65, is a brake drum 69. A brake band 70, arranged to engage said brake drum, is operated by means of a bell crank 71, link 72 and a hand lever 73. 74 is a spring seat for the driver and 75

15 is a draft yoke attached to the housing.

The steering of the machine is accomplished entirely through the medium of the planetary gears located in the hub and controlled by the brake 70. Normally in driving 20 ahead the brakes are set so as to hold the brake drum 69, the sleeve 65 and the planetary gears 63 against rotation relative to the shaft 22. Slipping the brakes equally correspondingly varies the speed; releasing one 25 brake or slipping it and holding the other causes the machine to turn to the side on which the brake that has been slipped or released is located.

From the foregoing it is seen that controlling 30 means are thus provided to vary the operation of the planetary gears in the well known manner and cause the sprockets to drive forward at various speeds. Since each drive sprocket is provided with a self-contained reduction gear of this sort, it is 35 obvious that each track may be positively driven forward or reversed in unison or at different speeds by manipulating the hand levers 73 and gear shifting lever 47. By arranging 40 the planetary gears within the drive sprocket the entire width of the tractor as a whole is greatly reduced without necessitating any undesirable reduction in the size of the gears. Furthermore, this construction permits 45 a very effective system of lubrication for the gears and eliminates the expensive steering friction clutches heretofore employed for steering tractors of this type.

It is obvious that various changes and variations 50 could be made in the structure described herein without departing from the spirit of the invention as set forth in the appended claims.

Having thus described my invention, what I claim and desire to secure by Letters Patent is—

1. A tractor comprising a motor having an extended crank case, a pair of self-laying track mechanisms arranged one on either 60 side of said motor, an equalizer bar connecting the front end of said track mechanisms and forming a central pivotal support for the front end of the crank case, and stub axles carried on either side of the rearward 65 extension of the crank case to support the

rear end of the motor on the track mechanisms.

2. A tractor comprising a motor having a unitary crank case and a transmission housing, a self-laying track mechanism at each 70 side of said motor, said track mechanisms having self-contained speed-changing gears, an equalizer bar connecting the front end of said track mechanism and forming a central pivotal support for the front end of the 75 crank case, and stub axles carried on either side of the transmission housing to connect the rear ends of the track mechanisms and support the motor thereon.

3. A self-laying track mechanism comprising an endless chain track, a truck frame having rollers engaging the ground run of the track, driving and carrying wheels about which the track travels, speed-changing gears carried interiorly of the driving wheel, 85 and means whereby said wheel may be driven at various speeds.

4. A self-laying track mechanism comprising an endless chain track, a truck frame having rollers engaging the ground run of 90 the track, driving and carrying wheels about which the track travels, planetary gears carried interiorly of the driving wheel, and a brake whereby said wheel may be driven at various speeds.

5. A tractor comprising a motor, a self-laying track mechanism secured to either side thereof, means to transmit power from said motor to the track mechanisms, said mechanisms comprising an endless chain 100 track, a truck frame having rollers engaging the ground run of the track, driving and carrying wheels about which the track travels, and speed changing gears carried interiorly of the driving wheel whereby said 105 wheels may be driven at various speeds.

6. In a traction engine having its entire weight supported upon a pair of self-laying tracks actuated by drive sprockets, the combination of means for steering the machine comprising speed changing gears carried 110 interiorly of each drive sprocket, and means whereby the operation of said gears may be varied to steer the traction engine.

7. In a traction engine having its entire weight supported upon a pair of self-laying tracks actuated by drive sprockets, the combination of means for steering the engine comprising planetary gears carried 115 interiorly of each drive sprocket, and controlling brakes whereby the operation of said gears may be varied to steer the traction engine.

8. In a traction engine having its entire weight supported upon a pair of self-laying tracks actuated by drive sprockets, the combination of means for steering the machine comprising drive sprockets having self-contained speed-changing mechanisms, and controlling means whereby the opera- 120 125 130

tion of said mechanisms may be varied to steer the traction engine.

9. A drive sprocket for self-laying track tractors comprising a drum, a drive shaft 5 rotatably journaled in said drum, a toothed rim carried exteriorly of the drum, an internal gear carried interiorly of said drum, and controllable planetary gearing interposed between the drive shaft and the internal gear.

10. The combination with the drive shaft of a self-laying track tractor, of a drive sprocket having a toothed rim provided with an internal gear, planetary gears connecting the drive shaft and the internal gear, and means to control the planetary gears to drive the sprocket at varying speeds.

11. A variable speed drive sprocket for self-laying track tractors comprising an oil tight drum, a drive shaft on which said drum is journaled, and gearing within said drum whereby said shaft may drive the drum at various speeds.

12. A variable speed drive sprocket for self-laying track tractors comprising an oil tight drum rotatably mounted on a drive shaft, a toothed rim carried on the outside of the drum, an internal gear carried interiorly thereof, a sleeve rotatably carried on the drive shaft and extending into the drum, and planetary gears carried by said sleeve and meshing with the internal gear on the interior of the drum and a pinion gear on the drive shaft.

13. A variable speed drive sprocket for self-laying track tractors comprising an oil tight drum rotatably mounted on a drive shaft, a toothed rim carried on the outside of the drum, an internal gear carried interiorly thereof, a sleeve rotatably carried on the drive shaft and extending into the drum, planetary gears carried by said sleeve and meshing with the internal gear on the interior of the drum, a pinion gear on the drive shaft, and a brake drum carried by said sleeve and provided with a brake band whereby the operation of the planetary gears may be controlled.

14. A tractor comprising a motor, a self-laying track mechanism secured to each side of said motor, and means to drive said track mechanisms forward or reverse or at various speeds to steer the tractor, said means including a transmission mechanism, a drive shaft, and drive sprockets rotatably mounted on said shaft, each of said sprockets comprising an oil tight drum, an internal gear carried interiorly thereof, and controllable planetary gears whereby said drum may be driven by the drive shaft at various speeds independently of the other drum.

15. A tractor comprising a motor, a self-laying track mechanism secured to each side of said motor, means to drive said track

mechanisms forward or reverse or at various speeds to steer the tractor, said means comprising a transverse drive shaft and drive sprockets rotatably mounted thereon, said sprockets comprising an oil tight drum, a toothed rim carried exteriorly and an internal gear carried interiorly thereof, a sleeve rotatably carried on the drive shaft and extending into said drum, and planetary gears carried by said sleeve and meshing with said internal gear and a pinion on the drive shaft.

16. A tractor comprising a motor, a pair of self-laying track mechanisms, and means to secure said mechanisms to the motor, said means including supports carried on either side of the motor, and resilient means to support the front end of the motor upon and midway between the track mechanisms.

17. A tractor comprising a motor, a pair of self-laying track mechanisms, means to secure said mechanisms to the motor, said means including stub axles to support one end of the motor upon the track mechanisms, and an equalizer spring extending from one track mechanism to the other and provided with a central pivotal support for the front end of the motor.

18. The combination of a driving sprocket containing a hollow hub, reduction gears of the planetary type in the hollow hub, and a brake for controlling the planetary gears.

19. The combination of a driving sprocket containing a hollow hub, reduction gears of the planetary type in the hollow hub, a brake for controlling the planetary gears, and means for entirely housing in the gears in the hub against the ingress of dirt.

20. The combination of a drive shaft, a planetary gear set thereon, a sprocket with an internal gear meshing with the planetary gears, said sprocket mounted for independent rotation on the drive shaft, a brake drum rotating with the planetary gears, and a brake band operative on the brake drum.

21. In a traction engine, the combination of a pair of endless, self-laying tracks laying side by side and spaced from each other, roller trucks within the self-laying tracks, load supporting means bearing upon the trucks and comprising a combined engine and transmission case with the forward end of the same supported by an equalizing bar on the forward ends of the trucks, and outriggers at the rear end of the transmission case bearing on the rear end of the trucks and on which outriggers the trucks pivot.

22. In a chain track tractor, a motor, a propeller shaft operatively connected with the motor, a housing for the propeller shaft also connected with the motor at one end, an axle operatively connected with the propeller shaft and extending transversely thereof, a housing for the axle connected with the housing for the propeller shaft,

a sprocket wheel carried at each end of the axle for driving a chain track, a roller truck mechanism for each chain track, a bracket extending outwardly at either side of the 5 propeller shaft housing and connected with the adjacent truck mechanism for supporting the weight of the tractor thereon, and an equalizer bar extending between opposite truck mechanism and on which the motor 10 is pivotally supported, said motor, propeller shaft, and axle housing constituting

the main frame of the tractor, the whole being supported upon the truck mechanisms at three points.

In testimony whereof I have hereunto set 15 my hand in the presence of two subscribing witnesses.

ELMER E. WICKERSHAM.
